Primary Examiner — Terry Wallace(74) *Attorney, Agent, or Firm* — Epstein Drangel LLP;
Robert L. Epstein(57) **CLAIM**

The ornamental design for a combination peeler and holder, as shown and described.

DESCRIPTION

FIG. 1 is a left perspective view of the combination peeler and holder showing my design;

FIG. 2 is a front elevation view thereof;

FIG. 3 is a rear elevation view thereof;

FIG. 4 is a left-side elevation view, the right-side is a mirror image thereof;

FIG. 5 is a top elevation view thereof;

FIG. 6 is a bottom elevation view thereof;

FIG. 7 is a top plan view of the holder thereof, shown separately for clarity of illustration; and,

FIG. 8 is an exploded perspective view thereof.
